CLAIM

The ornamental design for the paper trimmer, as shown and described.

DESCRIPTION

FIG. 1 is a perspective view of a paper trimmer showing my new design in the lowered position;

FIG. 2 is a top plan view thereof;

FIG. 3 is a right side elevational view thereof;

FIG. 4 is a front elevational view thereof, the rear view being a mirror image thereof;

FIG. 5 is a bottom plan view thereof;

FIG. 6 is a left side elevational view thereof; and,

FIG. 7 is a perspective view of the paper trimmer showing my new design in the raised position.

The broken line showing of the apertures formed in the base of my new design is for illustrative purposes only and forms no part of the claimed design.
